UNITED STATES PATENT OFFICE

MARCUS B. BEHRMAN, OF BROOKLYN, NEW YORK, ASSIGNOR TO AMERICAN SAFETY RAZOR CORPORATION, OF BROOKLYN, NEW YORK, A CORPORATION OF VIRGINIA

DESIGN FOR A RAZOR

Application filed January 8, 1931. Serial No. 38,242. Term of patent 14 years.

To all whom it may concern:

Be it known, that I, MARCUS B. BEHRMAN, a citizen of the United States, residing in Brooklyn, county of Kings, and State of New York, have invented a new, original, and ornamental Design for a Razor, of which the following is a specification, reference being had to the accompanying drawing, forming part thereof.

Figure 1 is a perspective view of a razor showing my new design, with the guard in open position; and

I claim as my invention:

The ornamental design for a razor substantially as shown.

MARCUS B. BEHRMAN.
